CLAIM

The ornamental design for an isokinetic oscillating exerciser, as shown and described.

DESCRIPTION

FIG. 1 is a perspective view of an isokinetic oscillating exerciser showing my new design;

FIG. 2 is a front elevational view thereof, the rear view being a mirror image thereof;

FIG. 3 is a right side elevational view thereof, the left side view being a mirror image thereof; and

FIG. 4 is a top plan view thereof, the bottom view being a mirror image thereof.

FIG. 1

FIG. 2

FIG. 4

FIG. 3
